ELECTRIC ATTACHMENT PLUG

Johann G. Peterson, West Hartford, Conn.

Application June 18, 1928. Serial No. 286,313

6 Claims. (Cl. 173—343)

My invention relates to electric attachment plugs.

It has for its object to provide an improved attachment plug. Another object of my invention is to provide such an improved plug wherein, while an effective and safe construction is produced, the parts are so simplified and arranged as to enable the plug to be manufactured at small expense. A further object of my invention is to provide an improved and rigid arrangement and construction of parts whereby the base, shell, insulating disc, and contacts are disposed in and cooperate in an improved manner. A still further object of my invention is to provide an improved plug having improved and simplified means for preventing relative rotation of the parts, and, more particularly, an improved axial interlock so disposed and co-operating with the other parts of the mechanism as not only to interlock the parts positively, but to enable a rigid construction to be produced having all the vital parts of the mechanism compactly disposed in an improved and effective manner in the relatively narrow zone extending transversely, i. e. vertically, across the plug through its axis, and in which the longitudinal contact apertures in the base are disposed on opposite sides of said axis. These and other objects and advantages of my invention will, however, hereinafter more fully appear.

In the accompanying drawing I have shown, for purposes of illustration, two forms which my invention may assume in practice.

In the drawing,—

Figure 1 is a plan view of a plug constructed in accordance with one form of my improvement; Fig. 2 is a vertical sectional view on line 2—2 of Fig. 1;

Fig. 3 is a similar view with the end or center contact, cooperating contact, and disc removed and showing the parts below the disc, and

Fig. 4 is a plan view with the center contact removed, showing the parts below the same.

In the illustrative construction of Figs. 1 to 4, I have shown an insulating base 1 having usual parallel contact apertures 2 in which are disposed contact members 3 and 4 of substantially equal width with the apertures and respectively connected to a threaded conducting shell 5 and a raised hollow central end contact member 6, the latter being insulated from the shell parts by a flat insulating disc 7, and suitably attached to the base by axial means, herein in the form of an axial rivet 8 embedded in the base 1 and holding all the parts together.

In my improved construction, it will be noted that the base 1 is provided with a flat upper end 9 on its periphery and at its axis is provided with a short axial extension 10 between the apertures 2. This extension 10 is preferably disposed substantially in the same transverse zone as the contacts 3 and 4. Herein the same is shown as slightly wider than the latter and having several sides. Although a smaller or a larger number of sides may be provided on this extension if desired, it preferably has four sides, as this produces an exceedingly simple and satisfactory construction, as will hereinafter appear. Herein it will also be noted that the shell 5 is provided with a plane top 11 and with a single enlarged rectangular opening 12 therein, herein forming a combined interlocking and contact opening and of sufficient width to fit opposite sides of the extension 10 and interlock therewith to prevent relative rotation of the shell and base, and of sufficient length to expose one of the openings 2 and provide a clearance around one edge thereof while only exposing a part of the aperture 2 on the opposite side of the extension 10. Moreover, it will be noted that not only is an axial interlock provided, in the transverse zone of the contact apertures 2 and between the latter, but that all of the edges of the aperture 12 are supported on the body around the axis of the latter substantially in said transverse zone, herein both along the elongated sides of the aperture and at the opposite ends thereof. It will also be noted that the body or base has portions which inclose the upper ends of the apertures 2 at the same time that they provide effective supporting means for the portions of the shell in the transverse zone of the apertures 2 and between the latter and the periphery of the shell, while the base herein also supports the entire periphery of the shell. Thus, it will be noted that both a base 1 and shell 5 of exceedingly simple and inexpensive structure are provided which cooperate to produce an exceedingly rigid structure well adapted to resist longitudinal or other pressures without crushing. It will also be noted that assembly is facilitated, as the shell 5 may be placed in a plurality of positions on the base 1, i. e. in the position shown in Fig. 3 or in a position wherein the shell is turned at 180° relative to the plug. Further, it will be noted that in either of these positions, due to the cooperation of the extension 10 and opening 12, the shell and base are locked against relative rotation. More particularly, it will be noted that the elongated edges of the opening 12 in the shell each extend to opposite sides of the axis of the latter in substantial parallelism, 110

while the interlocking portion 10 of the base is so located between the same as to provide axial interlocking means of a most effective character regardless of the direction of the twisting movement 5 of either the base or shell.

Through the portion of the opening 12 which extends only part way over the aperture 2, the shell contact 3 is extended, the same herein having a lateral extension 13 thereon adapted to engage 10 the outer surface of the plane top of the shell and laterally spaced from the axial interlock in the transverse zone of the apertures 2 and axial connecting means 8, while disposed in that zone transversely of the shell and extending toward 15 the periphery of the latter. Preferably, the contact 3 also has a laterally bent portion 14 intermediate its ends enabling the contact not only to have the desired resiliency and engage walls of the aperture 2, but to be snapped down 20 into position through the top of the shell and located and held properly in its aperture 2. Moreover, it will be noted that the insulating disc 7 overlies this lateral extension 13. Herein, the disc also has a rectangular aperture 15 there- 25 in adapted to fit the extension 10 on the base 1 and thus interlock the disc and base against relative rotation. As shown, the disc 7 also has a shorter slot 16 at one end of this aperture 15, of the width of the contact 4 and adapted to permit 30 the passage of that contact so that a lateral extension 17 thereon, also perforated to permit passage of the rivet 8, may overlie the disc, as shown in Fig. 2. If desired, the height of the extension 10 may be varied slightly, but preferably the 35 thickness of the disc 7 and the height of the extension 10 are such that when the disc 7 is in position, the outer surface of the extension 10 is not higher than the outer surface of the disc 7. Thus, when the contact 4 is inserted from the 40 top of the disc into the aperture 2 through the slot 16 in the disc and through one end of the aperture 12 in the shell, the usual lateral extension 17 on the contact 4 is enabled to extend across the axis of the base. It will also be noted 45 that it rests flat on the outer surface of the disc 7 in such position that when the raised hollow central contact 6 is riveted to the outer end of the rivet 8, an effective support is provided for both the contacts 4 and 6 and effective contact made 50 with the flange of the contact 6 at opposite sides of the base of the latter.

As a result of this improved construction, it will be noted that it is made possible to provide a plug of standard type with an axial interlock heretofore only provided in plugs having long high necks and a weak skeleton type of shell and base construction unadapted to withstand longitudinal pressure or twisting, or a construction incapable of use with a standard type of plug 55 wherein a lateral extension on one contact overlies the disc and supports the raised end contact. Moreover, it will also be noted that while obtaining the above advantages, an exceedingly simple and inexpensive interlock is provided between 60 the shell and base and one wherein the abutting parts engage one another to such an extent and along such elongated, herein parallel, paths on opposite sides of the axis as to produce a most effective interlock. Attention is moreover directed to the location of the structure on the base in the same general transverse zone as the contacts and between the contact apertures, to the rigid construction provided and heretofore described, and to the fact that my improvement is also 65 especially adapted to use with plugs having axial

holding means without in any way interfering with the latter since they are also disposed in that zone.

As a result of providing both an axial interlock and its co-operating parts in substantially the transverse zone of the contacts, it will also be evident that, if desired, since they are outside this zone, the sides of the inner end of the base may be reduced or cut away to points outside the edges of this zone in such manner as to reduce substantially the amount of material required in the base and thereby permit the use of bases of more expensive material such as bakelite or the like. Here, however, it will be noted that, while I show a structure adapted to be used with a base having such cut away or slabbed off sides, I do not claim a base having such cut away or slabbed sides. It will further be noted that even with the sides thus cut away, and while using a form of skeleton type structure inside the shell, it is still possible to provide a strong and rugged plug structure since the shell is supported in a very effective manner by supports in the zone in question including peripherally located supports at the ends of the zone and also supports surrounding the axis and between the peripheral supports. It is also possible to obtain the advantages of enclosing within insulating walls or chambers, the portions of the contacts which are inside the shell. Thus, it is made possible to produce a markedly more strong and safe construction as compared with a crushable construction having the isolated upstanding central post previously used in such bakelite plugs and wherein the shell is supported on a narrow ledge at only one side of this post, and the portions of the contacts inside the shell have no insulation between the same and the shell to prevent contact following twisting off or crushing.

Attention is further directed to the fact that as a result of my improved construction, it is also possible to eliminate all need for special and additional axial stiffening means within the end contact and in addition to the rivet or other axial connecting means, such as have been provided in such single post constructions in an attempt to prevent crushing. It will further be observed that my improved construction makes it possible to eliminate any need for extra axial contact connections with the lateral extension on the contact extending through the insulating disc and lying on the outer surface of the same, such as have heretofore been used in such single post constructions. My improved construction also makes it possible for the base of the end contact to engage directly with this lateral extension on opposite sides of the axial connecting means, while also enabling the end contact to be riveted to the base in such manner as to clamp this lateral extension against the insulating disc in a normal and effective manner without danger of crushing.

The insulating disc and base are also herein effectually interlocked due to the interlocking of the extension 10 with the disc. The contacts 3 and 4 are also held securely in position against rotation due to this interlocking of both the disc and shell with the base, and the fact that each contact extends through one interlocked member while the lateral extension on the contact 3 is clamped between two interlocked members. Thus, the only part which can by any chance revolve is the raised contact 6, and even should this work free for rotation relative to its rivet, it will be evident that the flange on its face will

always be in contact with the lateral extension 17 of the contact 4. The rivet also is shortened as compared with those heretofore used in previous constructions, by an amount equal to the combined thickness of the disc and the top of the shell, thereby enabling a reduction in the cost of the rivet. Through my improved construction, the shell, while strong, is also simplified and cheapened, the opening therein being readily and cheaply formed, while all need for other shell apertures and rotation preventing means and interlocks between the shell and base and the shell and contacts is eliminated. It will also be noted that the interlocking means on the base is readily and cheaply formed and that the same is not subject to breakage. These and other advantages will, however, be clearly apparent to those skilled in the art.

If desired, I may slightly shorten the lateral extension 17 in such manner that its free end, while extending beyond the perforation, does not underlie the flange on the end contact. Such a construction further cheapens manufacture and further provides an equal thickness of metal and insulation on opposite sides of the extension on the base, and is especially adapted to use when, as preferably, the disc is formed of fiber or other insulating material having some give, since it enables the parts to be more closely clamped together.

While I have in this application specifically described one embodiment which my invention may assume in practice, it will be understood that the invention is not limited thereto but may be further modified and embodied in various other forms without departing from its spirit or the scope of the appended claims.

What I claim as new and desire to secure by Letters Patent is:—

1. In an attachment plug, the combination with a plug body having spaced longitudinal contact apertures on diametrically opposite sides of its axis, shell interlocking means on one end of said body substantially axially located and on diametrically opposite sides of said axis between said apertures and disposed therewith in a zone materially narrower than said body and passing vertically through said axis, and shell supporting means in said zone at the same end of said body disposed substantially around said shell interlocking means and axis, of a shell provided with contact aperture means substantially in said zone and also having in said zone both means interlocked with said interlocking means and means disposed substantially around the latter and supported on said supporting means, an apertured insulating disc outside said shell, connecting means having a connecting member out of contact with said shell and disposed coaxially therewith in said body, an end contact member outside said disc and positioned by said connecting means, and contact members extending into said contact apertures having portions in said zone independent of said interlocking means and on opposite sides of said disc insulated from one another and electrically connected respectively to said shell and end contact member.

2. In an attachment plug, a plug body having one end adapted to be received in the lower open end of a shell, longitudinal contact apertures in said body on diametrically opposite sides of its axis disposed in a zone materially narrower than said body and extending vertically through said axis, shell interlocking means on one end of said body substantially axially located and on diamet-

rically opposite sides of said axis between said apertures and substantially in said zone, and shell supports on the same end of said body including supports in said zone at the opposite ends of said interlocking means and additional supports substantially in said zone at the opposite sides thereof, of a shell having an upper substantially closed end provided with contact aperture means substantially in said zone, and also having substantially in said zone both means interlocked with said interlocking means and means disposed around the latter supported on said end and side supports, connecting means having a connecting member out of contact with said shell and disposed coaxially therewith in said body, an apertured insulating disc outside said shell, an end contact outside said disc and positioned by said connecting means, and contact members extending into said contact apertures and having portions in said zone independent of said interlocking means and on opposite sides of said disc insulated from one another and electrically connected respectively to said shell and end contact.

3. In an attachment plug, the combination with a plug body provided with spaced longitudinal contact apertures on diametrically opposite sides of its axis, contact enclosing portions forming extensions of said apertures disposed at the inner end of said body and extending substantially throughout the length of the contacts, shell interlocking means on the same end of said body and on diametrically opposite sides of said axis located between said portions and disposed therewith in a zone materially narrower than said body, of a shell having contact member aperture means substantially in said zone, spaced supporting portions extending across said zone and supported on said enclosing portions, and also means between said supporting portions and substantially in said zone interlocked with said shell interlocking means, an apertured insulating disc outside said shell, connecting means having an axial connecting member out of contact with said shell and seated in said body between said contact apertures, an end contact member outside said disc and positioned by said connecting means, and contact members extending into said contact apertures and insulated from one another having portions in said zone independent of said interlocking means and on opposite sides of said disc and electrically connected respectively to said shell and end contact member.

4. In an attachment plug, the combination with a plug body having spaced longitudinal contact apertures therein on diametrically opposite sides of its axis, a shell interlocking and supporting portion on one end of said body disposed with said apertures in a zone materially narrower than said body and extending vertically through said axis and having shell interlocking means on diametrically opposite sides of said axis and extending along said zone and shell supporting means at opposite ends of said interlocking means extending across said zone, of a shell substantially imperforate outside said zone and having aperture means in said zone including an opening substantially conforming to and disposed lengthwise of said portion and having its opposite side edges engaging with said portion between the ends thereof and its opposite ends supported on the ends of said portion, an apertured insulating disc outside said shell, connecting means having a connecting member out of contact with said shell and disposed axially in said body, an end contact member outside said disc and positioned by said

connecting means, and contact members extending into said contact apertures and having portions in said zone independent of said interlocking means and on opposite sides of said disc insulated from one another and electrically connected respectively to said shell and end contact member.

5. In an attachment plug, the combination with a plug body having one end adapted to be received in the lower open end of a shell, longitudinal contact apertures in said body on opposite sides of its axis disposed in a zone materially narrower than said body and extending vertically through said axis, and a shell interlocking and supporting portion at one end of said body and disposed substantially in said zone having shell interlocking means substantially axially located on opposite sides of said axis and extending beyond the same in two directions between the ends of said portion and shell supporting means at the opposite ends of the latter, of a shell having contact aperture means disposed substantially in said zone, means substantially in said zone interlocking with said axially located means, and means in said zone supported on said supporting means at the opposite ends of said axially located means, an apertured insulating disc outside said shell, connecting means having a connecting member out of contact with said shell and disposed coaxially therewith in said body, an end contact outside said disc and positioned by said connecting means, and contacts extending into said contact

apertures having portions in said zone independent of said interlocking means and on opposite sides of said disc insulated from one another and electrically connected respectively to said shell and end contact member.

6. In an attachment plug, the combination with a plug body having spaced longitudinal contact apertures therein, shell interlocking means between said apertures comprising an axial projection projecting upward on one end of said body and having interlocking portions on diametrically opposite sides of said axis, and shell supporting portions on the same end of said body at opposite ends and opposite sides of said projection and below the top of the latter, of a shell seated on said body, having portions disposed around said projection, supported on said shell supporting portions and also having contact aperture means and spaced interlocking means engageable with said interlocking portions, an apertured insulating disc outside said shell having an aperture therein interlocked with said axial projection on the plug body, an axially disposed end contact member outside said disc, connecting means connecting said end contact member to said body, and contact members extending into said contact apertures in the body and having portions of the same independent of said interlocking means and on opposite sides of said disc insulated from one another and electrically connected respectively to said disc and end contact member.
